(57) **CLAIM**

We claim the ornamental design for an enclosure for a camera, as shown and described.

DESCRIPTION

FIG. 1 is a bottom front perspective view of an enclosure for a camera;

FIG. 2 is a bottom plan view of the enclosure for a camera; FIG. 3 is a top plan view of the enclosure for a camera; FIG. 4 is a front elevation view of the enclosure for a camera;

FIG. 5 is a rear elevation view of the enclosure for a camera; FIG. 6 is a left side view of the enclosure for a camera; and, FIG. 7 is a right side view of the enclosure for a camera.

The broken lines depict portions of the enclosure for a camera in which the design is embodied that form no part of the claimed design.
